UNITED STATES PATENT OFFICE

ANGELO B. D'IPPOLITO, OF VINELAND, NEW JERSEY

DESIGN FOR A CLASS RING

Application filed November 28, 1930. Serial No. 37,820. Term of patent 3½ years.

To all whom it may concern:

Be it known that I, ANGELO B. D'IPPOLITO, a citizen of the United States, residing at Vineland, in the county of Cumberland and State of New Jersey, have invented a new, original, and ornamental Design for Class Ring, of which the following is a specification, reference being had to the accompanying drawing, forming a part thereof.

Figures 2 and 3 are left and right end views, respectively.

I claim:

The ornamental design for a class ring, as shown.

ANGELO B. D'IPPOLITO.
